SNAP SWITCH

Gerhardt Blair, New York, N. Y.

Application March 6, 1943, Serial No. 478,178

3 Claims. (Cl. 200—67)

1

The present invention relates to electric switches, and more particularly to that type of switch known as a toggle switch.

In toggle switches now in use the bifurcated arm that supports the spring is urged into and out of engagement with a pair of flat spring contact members, and these members usually grasp the bifurcated arm very tightly, so that when the circuit is on and it is desired to turn it off, it is difficult to remove the arm from the spring contact members with any great speed, since a potential energy built up by the toggle spring causes a slippage of the bifurcated arm between the contacts before the toggle spring is on dead center. When the bifurcated arm slips partially away from the contact members, particularly when a heavy load of current is carried, there will be considerable sparking between the arm and the contact members. This sparking will of course eventually burn out the switch and make it absolutely worthless.

The present invention obviates the above difficulties, by eliminating the closing of the contacts by the bifurcated arm.

Another important object of the present invention is to provide all the advantages of the toggle switch, such as the bifurcated arm and the use of the dead center spring action, in conjunction with a movable contact arm.

According to another object the toggle is not to be part of any circuit and is, as a matter of fact, normally not in any contact with the circuit making and breaking device.

A further object of the present invention is to provide a means in conjunction with a toggle mechanism, for a positive action in opening and closing the contacts in an exceedingly abrupt and instantaneous manner, at the moment when the toggle reaches its maximum dynamic momentum.

Indeed the current is to be broken by knocking the parts out of contact, by a sharp blow.

Other objects and advantages of the present invention, will be obvious as brought out in the following specification and drawings which illustrate the invention, but are not to be interpreted in limitation thereof.

In those accompanying drawings similar reference characters indicate corresponding parts throughout the several views, in which,

Fig. 1 is a fragmentary view of a switch box showing the present invention in plan view, with the contacts closed;

Fig. 2 is a view similar to Fig. 1 showing the contacts open;

2

Fig. 3 is a cross-section on the line 3—3 of Fig. 1; and

Fig. 4 is a right hand end view of Fig. 1.

The drawings show, by way of illustration only, a fragmentary, insulated switch box 10. It contains a toggle switch mechanism and the usual bifurcated arm 11 is pivoted at 12 and 13 in bearing plates 14 and 15. A toggle spring 16 under compression engages at one end over a protuberance 17 at the yoke 18 of the arm 11 and is threaded through an eye 19 at its other end.

The eye 19 is one end of a bell crank lever 20, which is pivoted at 21 on a pin 22 mounted in the bearings 14 and 15. The other end of lever 20 carries a finger push button 23 which actuates the bifurcated arm by way of the toggle spring 16.

A contact arm 26 rides on a pin 27 which is pivoted in a pair of opposed bearings 24 and 25 and which carries a small coil spring 28.

The contact arm terminates in a contact bridge plate 29, which is integral with a short arm 30. The arm 30 is fixedly connected to but insulated from another angular arm 31 by a bolt and nut 33 and 34, and a plurality of insulated spacer discs 32 and an insulated bushing 35, respectively. The arm 31 has a pair of integral ears 36 which are journaled on the pin 27 in order to support the arms 30 and 31. The arm 31 is bent at an acute angle and terminates in a leg 37 the purpose of which will be hereinafter described.

As shown in Fig. 4 the contact bridge plate 29 serves to connect electrically the two terminals 38 and 39. These are at right angles to the switch arm 26 and are insulated by bushings 40. Bridge plate 29 carries the current from one terminal to another without passing through any part of the bifurcated arm or the toggle spring 16. The shanks 41 of the terminals 38 and 39 terminate in threaded binding posts 42 which support the ends 40 of the wires 43 and 44 between which contact is to be made and broken, those wires forming part, for instance, of the circuit fed by a source of supply 45. The wires 43 and 44 are fixed to the binding posts 42 by a pair of nuts 46 and 47.

In operating the switch shown in Fig. 1, wherein it is shown closed, the finger piece 23 is moved over in a clockwise direction until the toggle spring 16 snaps the bifurcated arm 11 upwardly, in counterclockwise direction. Thereupon the yoke 18 of the arm 11 strikes the end 37 of the arm 26, which swings clockwise and breaks the contact between the terminals 38 and 39 and the bridge plate 29. The end 37 of the arm 31 comes to a stop against the casing 10 as shown in Fig. 2. When it is desired to close the switch the ma-

nipulation of button is reversed and a converse action takes place with the exception that the coil spring 28 returns the arm 26 and bridge plate 29 into contact with the terminals 38 and 39 following the yoke 18 of the bifurcated arm 11 as the latter swings in a clockwise direction from the position of Fig. 2 into that of Fig. 1. The action of toggle spring 16 is, of course, stronger than that of coil spring 28.

Many modified forms of switch arm 26 may be made without departing from the principle of the invention.

I claim:

1. In an electric switch, a frame, a terminal insulatedly mounted in said frame, a contact arm comprising a contact suited for electric make and break connection with said terminal, a lever provided with one supporting arm upon which said contact is mounted, with pressure means reacting upon said frame and applying a torque to said lever which normally presses said contact into abutment with said terminal, and with another arm which extends from said one supporting arm substantially opposite to the direction in which said contact is pressed onto said terminal, a hammer arm spaced from said lever but adapted to be snapped onto said other arm thus swinging said lever counter to said torque into an open switch position in which said contact is removed from said terminal, and a manually controlled mechanism releasably engaging said lever in said open switch position.

2. In an electric switch, a frame, a pair of terminals spacedly and insulatedly mounted in said frame, a contact arm comprising a contact adapted to interconnect said terminals electrically, a lever provided with one supporting arm upon which said contact is insulatedly mounted, with pressure means reacting upon said frame and applying a torque to said lever which normally presses said contact into abutment with said terminals, and with another arm which extends from said one supporting arm substantially opposite to the direction in which said contact

is pressed onto said terminals, a hammer arm spaced from said lever but adapted to be snapped onto said other arm thus swinging said lever counter to said torque into an open switch position in which said contact is removed from said terminals, and a manually controlled mechanism releasably engaging said lever in said open switch position.

3. In an electric switch, a frame, a terminal insulatedly mounted in said frame and having a contact surface, a contact arm fulcrumed in parallelism with said surface upon said frame and comprising a contact suited for electric make and break connection with said terminal, a lever provided with one supporting arm upon which said contact is mounted, with pressure means reacting upon said frame and applying a torque to said lever which normally presses said contact into abutment with said terminal, and with another arm which extends from said one supporting arm substantially opposite to the direction in which said contact is pressed onto said terminal, a hammer arm fulcrumed in parallelism with said surface upon said frame and spaced from said lever but adapted to be snapped onto said other arm thus swinging said lever counter to said torque into an open switch position in which said contact is removed from said terminal, and a manually controlled mechanism releasably engaging said lever in said open switch position.
